UNITED STATES PATENT OFFICE.

GEORGE J. GREINER, OF DETROIT, MICHIGAN.

GASOLENE-TANK OUTLET.

1,054,533.

Specification of Letters Patent. Patented Feb. 25, 1913.

Application filed August 28, 1912. Serial No. 717,594.

To all whom it may concern:

Be it known that I, GEORGE J. GREINER, a citizen of the United States, residing at Detroit, in the county of Wayne and State 5 of Michigan, have invented new and useful Improvements in Gasolene-Tank Outlets, of which the following is a specification.

The present invention relates to improvements in gasoline tanks employed in connection with automobiles, motorcycles, motor 10 boats, etc.

In carrying out my invention it is my purpose to provide simple and effective means whereby a vehicle will be brought to 15 a stop after a certain amount of gasoline has been fed from the tank, in order to warn the operator of the machine that an additional supply of gasoline is required, sufficient fluid, however, being retained 20 within the tank and readily fed therefrom to propel the machine a suitable distance, as for instance to the nearest replenishing station.

With the above recited objects in view, 25 and others which will be more apparent as the nature of the invention is more fully described, the improvement resides in the construction, combination and operative arrangement of parts set forth in the following specification, and falling within the scope of the appended claim.

In the drawing, Figure 1 is an elevation of a gasoline tank partly broken away and provided with my improved outlet or feed 35 device. Fig. 2 is a similar view parts being broken away, and other parts being shown in section and illustrating the manner in which the fluid is fed from the bottom of the tank.

Referring now to the drawing in detail the numeral 1 designates an ordinary gasoline tank, and 2 a fuel outlet pipe which is secured to the bottom of the tank and which extends both within and below the tank. 40 The lower extending portion of the pipe is threaded for the reception of a suitable valved nipple (not shown). The pipe 2 is provided with a pair of spaced openings 3 and 4 respectively. The opening 3 is arranged adjacent the bottom of the tank, while the opening 4 is positioned a suitable distance away from the top of the tube 2, and also at a desirable point away from the opening 3. The pipe 2, above the opening 4 45 is provided with a bayonet slot 5, the purpose of which as well as that of the open- 50 ings 3 and 4 will be presently set forth. As illustrated in the drawing the pipe 2 terminates a considerable distance away from the upper portion or closure of the tank 1, and the said upper portion or closure is provided with a suitable opening 6 for the reception of a hollow rod or tube 7. The outer face of the rod or tube is adapted to be snugly received within the bore of the pipe 2, the frictional engagement therebetween being sufficient to prevent the leakage of the fluid from the tank, but at the same time permitting of the free movement of the tube within the pipe. The portion of the tube which extends through the opening 6 is provided with a head 8. The portion of the tube arranged within the pipe 2 is provided with spaced openings designated by the numerals 9 and 10 respectively. The opening 10 is adapted to coact with the opening 4, when the parts are in the position illustrated in Fig. 1, and the gasoline flows through the said openings and the tube when the supply in the tank is at a level above the said openings. 55 When the parts are as set forth the opening 9 is arranged a distance below the opening 3 corresponding with the length of the bayonet slot 5, so that the fluid cannot find an outlet through the said openings. The tube 7 is provided with a nib or projection 11, which passes through the bayonet slot. When the tube 7 is in the position illustrated in Fig. 1 of the drawing, the opening 10 of said tube is brought into register with the opening 4 of the pipe 2 and the fluid finds an exit from the tank through these registering openings. The openings 10 and 9 of the tube, it is to be understood, are out of the same vertical line so that the tube is 60 not only drawn in an upward direction so that its nib contacts with the upper wall of the bayonet slot, but the tube 7 must be rotated until the nib contacts with the inner wall of the angular passage of the bayonet slot before the opening 9 of the tube is brought into register with the opening 3 of the pipe. When the level of the fluid falls below the registering openings 4 and 10, it will be evident to the operator of the vehicle, through the stoppage of the machine 65 that only a small quantity of gasoline remains within the tank, the said quantity, however, being sufficient to propel the vehicle a certain distance, say nine or ten miles, which is generally sufficient to bring the vehicle to a garage or supply station. 70 75 80 85 90 95 100 105 110

After the stoppage of the vehicle the operator will, through the medium of the head 8 raise the tube 7 within the pipe 2 to bring the opening 9 of the said tube adjacent the 5 opening 3 of the pipe, and by partially rotating the tube, so as to cause the member 11 to engage within the offset portion of the bayonet slot, the opening 9 of the tube will be brought into perfect alinement with the 10 opening 3 of the pipe and the tube sustained in such position. The fluid will then, of course, flow through the openings 3 and 9, for propelling the machine a short distance as above set forth.

15 Having thus described the invention, what I claim is:—

A fluid tank for the purpose set forth, provided with a pipe which extends within the tank, said pipe being provided with an 20 opening arranged adjacent the bottom of the tank, said pipe being provided with a second opening disposed a distance from the first named opening, the pipe being further provided with a key hole slot, a tube extending 25 through the tank and frictionally en-

gaging with the bore of the pipe, said tube having its outer face provided with an extension which is received within the key hole slot of the pipe, said tube being further provided with an upper and a lower 30 spaced opening, and the lower opening of the tube adapted to be brought to register with the lower opening of the pipe when the tube is moved in one direction and to cause the upper opening of the tube to be brought 35 out of register with the upper opening of the pipe, and to cause the upper opening of the tube to be brought into register with the upper opening of the pipe, and the lower opening of the tube to be brought out of 40 register with the lower opening of the pipe when the tube is moved in a second or opposite direction.

In testimony whereof I affix my signature in presence of two witnesses.

GEORGE J. GREINER.
